WINDING APPARATUS

Adolph Potdevin, Garden City, and Robert L. Richmond, Yonkers, N. Y., assignors to Potdevin Machine Company, Brooklyn, N. Y., a corporation of New York

Application May 27, 1938, Serial No. 210,312

3 Claims. (CL 242—55)

This invention is directed to an improvement in winding apparatus and has for one of its objects the provision of an apparatus for drawing material from a supply roll and rewinding the same into separate rolls on separate shafts. The improved apparatus is particularly well adapted for use in connection with the rewinding of printed paper and slip sheet paper, although it is adapted also for rewinding paper which is drawn from a supply roll, slitted and then rewound into two separate rolls.

Slip sheet paper as used in printing today is usually a waxed paper and more recently a new type of slip sheet paper has been developed which is not only waxed but creped as well. With plain waxed slip sheet paper it is obvious that care must be exercised that the slip sheet be wound under the proper tension inasmuch as otherwise it will slide upon itself or telescope. On the other hand, with the waxed crepe paper it is evident that not only must precautions be taken in this same direction but care must be exercised that too much tension is not applied to the slip sheet paper inasmuch as this will take the crepe out of the paper.

In rewinding printing rolls it is usually desirable to obtain as large a rewound roll as can be handled, since, obviously, small rolls require more stoppage of the machine upon which they are ultimately used. Bearing this in mind, it is desirable, and it is made possible by the present invention, to be able to splice the printed sheet of a second supply roll to the roll which is already in the machine and continue to wind the printed paper from the second supply roll onto a single printed roll, and at the same time start rewinding a new slip sheet roll from the second supply roll.

In conventional machines of the prior art the rewinding shafts are generally driven by a friction device, such as friction clutches or slip belts. In order to produce rewound rolls of a desired hardness on each rewinding shaft, the friction devices on the respective rewinding shafts must be very carefully and continuously manipulated by the operator. Anyone with experience in the handling of this kind of apparatus will appreciate the difficulties of this procedure. With such friction driven apparatus, difficulties are encountered from the first starting of the rewinding, inasmuch as unless the frictions on the rewinding shafts are absolutely equally adjusted the rolls on one shaft are harder from the very beginning than the roll, or rolls, on the other shaft.

In the present invention this trouble is over-

come by the introduction of an equalizing but non-slipping differential gearing.

It is assumed that the shafts upon which the rolls are to be wound are of the same, or nearly the same, diameter; and as the rewind shafts of the present invention are differentially geared together the pull on each web or each lead of the same web of material is practically the same.

If the material wound onto the different shafts is of the same thickness, no further adjustment is required. The roll, or rolls, on each shaft will increase equally in diameter and will be of the same hardness, the hardness desired being obtained by the regulation of the tensioning or braking device on the parent or supply roll.

On the other hand, if the supply roll consists of two webs of paper of different thickness, wound onto one roll which is to be separated into two independent rolls, each wound onto its own shaft, the differential gearing which equalizes the tension on both rolls begins the winding of each roll on each shaft with the same hardness; but, as the material is of unequal thickness, the roll with the thicker material increases faster in diameter than the roll with the thinner material, producing an unbalanced condition of leverage which the differential gearing alone is not able to overcome.

In order to eliminate this difficulty a double braking device is incorporated in this invention, one on each rewind shaft. It is self-evident that with a differential alone the surface speed of the two or more rolls being wound remains the same; but the hardness of the rolls on the two shafts will vary due to the increase of diameter or leverage. The rolls with the thin material will become harder, and the rolls with the thicker material, which becomes larger in diameter, will become relatively softer.

By applying the brake on the shaft with the smaller diameter roll, the larger diameter rolls may be made of the same hardness as the small rolls, or even harder, if desired; or vice versa.

In the accompanying drawings:

Fig. 1 is a side elevational view of our improved apparatus;

Fig. 2 is a plan view of the same; and

Fig. 3 is a diagrammatic view of a modified embodiment of our invention.

Referring to the drawings in detail and with reference first of all to the rewinding into separate rolls of a printed web and a slip sheet web taken from a composite roll where the printed web and slip sheet have been wound together: 2 designates the side frames of the apparatus

supporting a driving motor 4, the armature shaft 6 of which carries a sprocket 8 for a sprocket chain 10. The chain 10 passes over a sprocket 12 mounted on the driven shaft 14 of a differential. The differential comprises enclosing housing 16, bevel gear 18 on the inner end of the shaft 14, crown gear 20 meshing with the gear 18, bevel pinions 22 carried by the crown gear 20 and crown gears 24 and 26 meshing with the pinions 22.

The bevel gear 26 is fast on a driving shaft 28 extending transversely of the machine and the bevel gear 24 is fast upon the other driving shaft 30 of the differential.

15 The shafts 28 and 30 are provided with brake drums 32 and 34, respectively, each drum being equipped with a conventional hydraulic brake. The brake for the drum 34 is actuated by a fluid supplied thereto through a conduit 36, pressure 20 on the fluid being varied by member 38. The brake for the drum 32 is actuated by fluid supplied through conduit 40, pressure on the fluid being varied by member 42.

10 The drum 34 carries a sprocket 44 for sprocket chain 46. This chain passes over a sprocket 48 mounted on a stub shaft 50 carrying a gear 52 meshing with a gear 54 which in turn meshes with a gear 56 rigidly mounted upon the rewinding shaft 58. The printed web 62 is drawn or 25 unwound from the supply roll 64 and rewound into a roll 60 on the rewinding shaft 58.

The drum 32 is provided with a sprocket 66 for sprocket chain 68. This chain passes over a sprocket 70 mounted on a shaft 72 which also 25 carries a gear 74 meshing with gear 76 in turn in mesh with gear 78 rigidly mounted on the rewinding shaft 80 upon which slip sheet web 84 which is drawn or unwound from the supply roll 64 is to be wound into a roll 82.

40 It will be understood that the supply roll 64 is a composite roll made up of the printed web 62 and the slip sheet web 84 rolled up together as they come from the printing press.

The printed web 62 as it passes from the roll 45 64 is led about rollers 88 and 90 carried by an adjustable bracket 86. The slip sheet web 84 as it passes from the roll 64 is led about rollers 96 and 98 mounted on adjustably mounted bracket 94.

50 The supply roll 64 is mounted on a shaft 102 carrying a pinion 104 meshing with a gear 106 on a stub shaft 108. This stub shaft carries a 55 brake drum 110 equipped with brake shoes 112. The adjustment of this brake is effected through shaft 114 equipped at its outer end with a hand wheel 116. The shafts 58, 80 and 102 are all mounted in open bearings in the frame 2, as will be seen from Fig. 1, so as to facilitate placement and removal.

60 It will be understood from all of the foregoing that in operation, after threading the machine, the brake shoes 112 are adjusted to apply the desired friction to the drum 110 to provide the proper combined tension on the materials being rewound. The motor 4 is then started to drive the printed web rewind shaft 58 and the slip sheet shaft 80 through the differential and chain and gear drive above described.

It will be appreciated that although the slip sheet and printed web may be of different thicknesses the differential will automatically compensate for the same to effect rotation of the 70 rewind rolls 60 and 82 at the same peripheral speed. As above pointed out, the tensions on the webs 62 and 84 are relatively adjustable. This

adjustment is effected by manipulation or adjustment of the brakes on the drums 32 and 34. This adjustment, that is to say, relative adjustment of the tension on the webs 62 and 84 permits the printed web 62, for instance, to be wound under greater tension than the slip sheet 84 which is of advantage particularly when dealing with crepe paper slip sheets inasmuch as it permits the printed web to be rewound into a tight roll, which is desirable, while at the same time the 10 tension on the slip sheet paper will be low enough to insure retention of the crepe in the paper. This ability to adjust the tension on the two webs is of further advantage where, when the supply roll 64 is nearly exhausted, it is desired 15 to splice the printed web from a new roll to the printed web of the nearly exhausted roll so as to make the rewind roll 60 of as large diameter as conveniently can be handled and where at the same time a new rewind roll of slip sheet paper is 20 started.

It is understood, of course, that the adjustment of the brake on the supply roll shaft will vary the total tension on the webs passing to the rewind shafts without, however, any substantial 25 variation in the relative tension on these materials; and that relative adjustment of the differential brakes will effect variation in the relative tensions on the webs being rewound without varying the total tension. 30

This ability to adjust the relative tension between two webs being rewound is also of advantage where instead of employing a composite roll the printed web is to be slit lengthwise and the two widths thus produced rewound on separate rolls. In such a case one rewind roll may be of a much greater width than the other and it is necessary to rewind the two rolls under different tensions. In this connection, we refer to the embodiment of our invention as illustrated in Fig. 3. It will be seen from this figure that the printed web passes over guide roll 130 between slitting rollers 136 and 138, one portion of the slit web passing over roller 140 to be rewound at 142, the other width passing under roller 144 to be rewound at 146.

It will be understood that various changes may be made in the details of construction and arrangement of parts as herein illustrated and described within the purview of our invention. 50

This application is a continuation in part of our copending application Serial No. 155,408, filed July 24, 1937.

What we claim is:

1. Rewinding apparatus for a supply roll of 55 superimposed webs of material comprising in combination a supply roll shaft, a plurality of rewind shafts, a differential for driving said rewind shafts to draw webs from the supply roll shaft and rewind them upon said rewind shafts, 60 and brakes for the driving shafts of the differential individually adjustable, thereby individually to adjust the tensions on the webs passing to the rewind shafts.

2. Rewinding apparatus for a supply roll of 65 superimposed webs of material comprising in combination a supply roll shaft, a plurality of rewind shafts, a differential for driving said shafts to draw webs from the supply roll shaft and rewind them upon said rewind shafts, a brake for 70 each of the driving shafts of the differential, said brakes being adjustable independently of each other to effect an adjustment in the relative tensions on the webs passing to the rewind shafts, and an adjustable brake for the supply 75

roll shaft governing the total tension applied to the webs being rewound.

3. Rewinding apparatus for a supply roll of superimposed webs of material comprising in combination a supply roll shaft, a plurality of rewind shafts, a differential for driving said rewind shafts to draw webs from the supply roll shaft and rewind them upon said rewind shafts, a brake for each of the driving shafts of the differential, said brakes being adjustable independently of each other to effect an adjustment in the relative tensions on the webs passing to

the rewind shafts from the supply shaft, and an adjustable brake for the supply roll shaft for effecting variation in the total tension applied to the webs being rewound, the total tension on the webs being rewound being unaffected by adjustment of the first mentioned brakes, and the relative tension on the webs being rewound being substantially unaffected by adjustment of the last mentioned brake. 5
